UNITED STATES PATENT OFFICE

CARL W. SCHWENZFEIER AND JOHN E. McLAUGHLIN, OF TOLEDO, OHIO, ASSIGNEES TO
OWENS-ILLINOIS GLASS COMPANY, OF TOLEDO, OHIO, A CORPORATION OF OHIO

GLASSWARE FORMING MACHINE

Application filed April 18, 1929. Serial No. 356,032.

Our invention relates to improvements in glassware forming machines and more particularly to the charge severing or cut-off mechanism associated with the blank or gathering molds and operating to sever the mold charges from the supply body of molten glass.

An object of the present invention is to generally improve the construction of the charge severing mechanism and provide means whereby exceptionally accurate adjustment of the position of the cut-off knife may be obtained without difficulty.

Another object is to provide means whereby the cut-off knife may be adjusted in two stages to its operative position, the first stage constituting a "coarse" adjustment by which a knife is quickly brought to approximately the proper operating position and a second stage constituting a "fine" adjustment by which the knife is set accurately in proper relation to the blank or gathering mold.

Other objects will be apparent hereinafter. In the drawing:

Fig. 1 is a side elevation showing the cut-off mechanism in conjunction with a blank mold.

Fig. 2 is a sectional elevation thereof.

Fig. 3 is a detail sectional view showing the improved adjusting means for raising and lowering the knife.

Fig. 4 is a sectional view taken along the line IV-IV of Fig. 3.

In the accompanying drawing, the cut-off mechanism is shown in conjunction with a suction blank mold 5 or gathering mold which cooperates with a neck mold 6 and blowing head 7 in the gathering of mold charges from the supply body of molten glass 8 and transformation of the mold charges into blanks or parisons. The lower end of the mold cavity opens thru the bottom of the mold 5 so that glass may be drawn into the cavity when the bottom of the mold contacts with the surface of the supply body of glass 8 in the container C.

The charge severing mechanism includes a knife 9 adapted to be moved laterally across the lower face of the blank mold. The knife is supported on the lower end of a vertical

rock shaft 10 which is journaled in upper and lower bearings 11 and 12 respectively. The lower bearing is carried by a bracket 13 extending horizontally from the blowing head 7. The upper bearing 11 (Fig. 2) is formed at the outer end of a horizontal arm or bracket 14 which forms part of a rotary mold carriage. The upper end of the shaft 10 is splined to a sleeve 15 thru which it extends, said sleeve being mounted for oscillation and reciprocation in the bearing 11. A spur gear 16 at the upper end of the sleeve 15 runs in mesh with a rack bar 17 mounted in a horizontal slideway 18 in the bracket 14. This rack bar is reciprocated at regular intervals to rock the shaft 10 and thereby impart a horizontal swinging movement to the cut-off knife 9.

A bell crank lever 19 is connected thru a yoke 20 (Fig. 2) to an intermediate portion of the sleeve 15 and is rocked periodically by means (not shown) to impart movement to the rock shaft in the direction of its length for the purpose of effecting relative vertical movement between the blank mold 5 and cut-off knife 9 after completion of each charge severing operation.

Adjustment of the cut-off knife 9 for the purpose of obtaining proper cooperation between the knife and corresponding blank mold is effected in two stages. The first or "coarse" adjustment is provided to obtain a quick movement of the knife to approximately the proper elevation or position with respect to the blank mold. The secondary or "fine" adjustment provides for movement of the knife to precisely the proper position with respect to the blank mold. The mechanism by which the above adjustments may be obtained includes a sleeve or collar 21 threaded upon the rock shaft 10 and carrying a hand wheel 22 which is manually rotatable. The lower end of the sleeve 21 is split in the direction of its length and formed with ears 23 connected by a lock screw 24. Adjustment of the screw 24 to bring the ears together serves to lock the sleeve against rotation on the rock shaft 10. Thus the lower end of the sleeve constitutes a clamp or locking device by which accidental rotation of the

sleeve is prevented. The upper end of the sleeve 21 is formed with an annular flange 25 extending radially outward and taking over and rotatable upon a flange 26 at the 5 lower end of a tubular connector 27 within which the flange 25 is confined. This connector 27 extends into a gear housing 28 formed at the lower end of the upper sleeve 15. The upper end 29 of the connector 27 is 10 threaded and extends into an annular chamber 30 where it engages internal threads 31 formed in the chamber. This connector rotatively secures the sleeves 15 and 21 together so that by rotating the hand wheel 22, the 15 rock shaft 10 upon which the sleeve 21 is threaded is moved in the direction of its length and thereby quickly changes the vertical position of the cut-off knife 9 with respect to the blank mold 5. This constitutes 20 what we term the "coarse" adjustment.

The construction providing for "fine" adjustment of the knife includes a worm gear 32 formed on the tubular connector 27 just below the threaded upper end 29, said gear 25 running in mesh with a worm 33 arranged within the gear housing 28 and mounted upon a horizontal shaft 34. This shaft 34 extends thru one end of the gear housing 28 and carries a hand wheel 35 which is manually rotatable. A spring pressed detent 36 (Fig. 4) is adapted to project into one of an annular series of recesses 37 to hold the shaft 34 against accidental rotation. By rotating the worm 33 and the worm gear 32 the connector 27 is rotated. Due to the threaded connection between the upper end of said connector and the gear housing 28 and rotary connection between the lower sleeve 21 and connector 27, said connector and the sleeve 21 40 will be moved vertically upward or downward with the result that the rock shaft 10 is moved up or down. Because of the worm drive between the shaft 34 and the connector 27 rotation of the worm 33 very slowly rotates the worm gear 32 with the result that an exceptionally fine adjustment of the knife 9 relative to the blank mold 5 may be obtained with ease.

Excessive downward movement of the connector 27 in obtaining fine adjustment of the knife is prevented by the presence of a stop 38 (Fig. 3) which projects thru one wall of the housing 28 into the path of downward movement of the threaded portion 29. As 50 shown in Fig. 3 the lower end of the threaded portion 29 comes in contact with the stop 38 after the sleeve has been adjusted down to a predetermined degree and prior to movement of the lower end of the connector entirely 55 without the housing.

In adjusting the cut-off mechanism embodying the above structure the hand wheel 22 is rotated until the knife is brot into approximately the proper position for severing 60 charges of glass in the mold from the glass in

the supply body. The small hand wheel 35 is then adjusted to obtain a "fine" setting of the knife 9. The spring pressed detent 36 prevents accidental changing of this "fine" setting. The hand wheel 22 which is operated to obtain the "coarse" adjustment may be locked against accidental rotation by setting the lock screw 24 so that the lower end of the sleeve 21 firmly grips the rock shaft. 10

Modifications may be resorted to within 75 the spirit and scope of the appended claims.

What we claim is:

1. In a glassware forming machine, the combination of a suction blank mold, a knife adapted to be moved laterally across the 80 charge receiving end of the mold, a vertical rock shaft supporting the knife, means including a hand wheel threaded on the shaft for adjusting said shaft in the direction of its length, and means to adjust the rock shaft 85 and hand wheel in unison in the direction of the length of the shaft with respect to the mold.

2. In a glassware forming machine, the combination of a support, a sleeve extending vertically thru and journaled in the support, means to oscillate and periodically reciprocate said sleeve, a rock shaft extending thru and splined to said sleeve, a cutoff knife at the lower end of the rock shaft, an adjusting 90 collar threaded on the rock shaft below said sleeve, a gear housing formed at the lower end of said sleeve, a tubular member arranged in part within the housing and having its upper end threaded into a portion of the 95 housing, gearing in said housing having a driving connection with said tubular member, and connection between the tubular member and collar whereby rotation of the latter moves the rock shaft relative to said tubular member and sleeve in a direction lengthwise of the rock shaft.

3. In a glassware forming machine, the combination of a support, a sleeve extending vertically thru and journaled in the support, 110 means to oscillate and periodically reciprocate said sleeve, a rock shaft extending thru and splined to said sleeve, a cutoff knife at the lower end of the rock shaft, an adjusting collar threaded on the rock shaft below said 115 sleeve, a gear housing formed at the lower end of said sleeve, a tubular member arranged in part within the housing and having its upper end threaded into a portion of the housing, connection between the tubular 120 member and collar whereby rotation of the latter moves the rock shaft in the direction of its length, and a worm and gear mechanism operable to rotate said tubular member and thereby adjust the collar, tubular member and 125 shaft axially as a unit.

4. In a glassware forming machine, the combination of a support, a sleeve extending vertically thru and journaled in the support, means to oscillate and periodically recipro- 130

- cate said sleeve, a rock shaft extending thru and splined to said sleeve, a cutoff knife at the lower end of the rock shaft, an adjusting collar threaded on the rock shaft below said 5 sleeve, a gear housing formed at the lower end of said sleeve, a tubular member arranged in part within the housing and having its upper end threaded into a portion of the housing, connection between the tubular member and 10 collar whereby rotation of the latter moves the rock shaft in the direction of its length, a worm and gear mechanism operable to rotate said tubular member and thereby adjust the collar, tubular member and shaft axially 15 as a unit, and means to limit the degree of adjustment obtainable by the worm and gear mechanism.
5. In combination a vertical rock shaft, a cutoff knife at the lower end of the shaft, a 20 support for the rock shaft, connection between the rock shaft and support whereby said rock shaft is free to oscillate and reciprocate in the support, means including a sleeve threaded on the rock shaft to adjust 25 said shaft axially, and additional means operable to adjust the shaft and sleeve as a unit in the direction of their length with respect to the support.
6. In combination a vertical rock shaft, a 30 cutoff knife at the lower end of the shaft, a support for the rock shaft, connection between the rock shaft and support whereby said rock shaft is free to oscillate and reciprocate in the support, means including a 35 sleeve threaded on the rock shaft to adjust said shaft axially, and a worm and gear device operable to adjust the shaft and sleeve as a unit in the direction of their length with respect to the support.
- 40 7. In combination a vertical rock shaft, a cutoff knife at the lower end of the shaft, a support for the rock shaft, connection between the rock shaft and support whereby said rock shaft is free to oscillate and reciprocate in the support, means including a sleeve threaded on the rock shaft to adjust said shaft axially, a worm and gear device operable to adjust the shaft and sleeve as a unit in the direction of their length with respect to 45 the support, and means to limit the degree of adjustment obtainable by the worm and gear device without limiting the extent of adjustment obtainable by the first named adjusting means.
- 55 8. In combination a vertical rock shaft, a cutoff knife at the lower end of the shaft, a support for the rock shaft, connection between the rock shaft and support whereby said rock shaft is free to oscillate and reciprocate in the support, means including a sleeve threaded on the rock shaft to adjust said shaft axially, additional means operable to adjust the shaft and sleeve as a unit in the direction of their length with respect to 60 the support, and locking devices individual 65 to said adjusting means to secure the latter against accidental movement.
9. The combination of a rock shaft, a knife thereon, a supporting element for the rock shaft, adjusting devices having screw threaded connection respectively with said supporting element and the rock shaft, and means providing a connection between the adjusting devices, preventing relative movement in a direction lengthwise of the shaft and permitting relative rotation of said devices. 70 75
10. The combination of a knife shaft, a supporting element for the shaft, an adjusting device having a screw threaded connection with the supporting element, and a second adjusting device having a screw threaded connection with the shaft, said adjusting devices being interconnected for relative rotation and held against relative movement in a direction lengthwise of the shaft. 80 85
11. The combination of a knife shaft, a supporting element for the shaft, an adjusting device having a screw threaded connection with the supporting element, a second adjusting device having a screw threaded connection with the shaft, said adjusting devices being interconnected for relative rotation and held against relative movement in a direction lengthwise of the shaft, and means for moving said shaft, supporting element 90 and adjusting devices up and down bodily as a unit. 95
12. The combination of a knife shaft, a supporting element for the shaft, an adjusting device having a screw threaded connection with the supporting element, a second adjusting device having a screw threaded connection with the shaft, said adjusting devices being interconnected for relative rotation, and held against relative movement in a direction lengthwise of the shaft, means for moving said shaft, supporting element and adjusting devices up and down bodily as a unit, means for rocking said unit about the axis of the shaft, and means for locking said adjusting devices against rotation relative to the shaft. 100 105 110
